UNITED STATES PATENT OFFICE.

MAX FRISCH, OF BERLIN, GERMANY.

PORTABLE WASHING APPARATUS.

SPECIFICATION forming part of Letters Patent No. 564,878, dated July 28, 1896.

Application filed June 1, 1896. Serial No. 593,814. (No model.) Patented in Germany June 12, 1895, No. 87,381.

To all whom it may concern:

Be it known that I, MAX FRISCH, a subject of the King of Prussia, German Emperor, residing at Berlin, German Empire, have invented a new and useful Improvement in Washing Apparatus to be Carried in the Pocket, (for which I have obtained a patent in Germany, No. 87,381, bearing date June 12, 1895,) of which the following is a specification.

The present invention relates to a washing apparatus to be carried in the pocket which can be used for preventing infection, for wounds, foot-sores, galling, &c.

The apparatus substantially consists of a bottle a, filled with an antiseptic liquid, and the two closures b and h. Closure b is provided with a washer d and a stopper c, while the other closure serves to hold a sponge f pressed together.

The apparatus can be conveniently carried in the pocket, for which purpose the bottle is of a shape which is adapted to the body.

The apparatus is used by unscrewing the cap h; taking out the sponge f, which, after removal of the stopper c, is imbued with the antiseptic liquid and used for washing the wound or sore place.

What I claim is—

A washing apparatus which can be carried in the pocket, consisting of the combination of a bottle a filled with an antiseptic liquid, with the closures b and h, of which the one b contains a washer d and a stopper c, the other one h serving to hold a sponge f, substantially as and for the purpose set forth.

In witness whereof I have hereunto set my hand in presence of two witnesses.

MAX FRISCH.
